BUILDING

Glenn Marvin Howell, Atlanta, Ga.

Application April 28, 1952, Serial No. 19,500

Term of patent 14 years

(Cl. D13—1)

To all whom it may concern:

Be it known that I, Glenn Marvin Howell, a citizen of the United States of America, residing at Atlanta, in the county of Fulton and State of Georgia, have invented a new, original, and ornamental Design for a Building, of which the following is a specification, reference being had to the accompanying drawing, forming part thereof, and wherein:

Fig. 1 is a front elevation of a building, embodying my new design.

Fig. 2 is an end view of the building shown in Fig. 1.

Fig. 3 is a view of the opposite end of the building shown in Fig. 1.

Fig. 4 is a plan view of the building shown in Fig. 1.

The back of the building is substantially plain.

I claim:

The ornamental design for a building, substantially as shown and described.

GLENN MARVIN HOWELL.
